END GROOVING APPARATUS FOR HOLLOW
TILE

James D. Thompson, Eureka, Calif.

Application March 28, 1939, Serial No. 264,674

11 Claims. (Cl. 25—1)

This invention relates to machine means for indenting mortar grooves into the ends of hollow tile, after they come from the forming machine, before burning.

5. The desirability of such a groove has long been apparent. Obviously they cannot be cut in the forming machine and can only be impressed or upset into the clay, in its somewhat plastic state, and various attempts to do this in the past are 10. of record.

15. Since the clay is plastic but practically incompressible, the material displaced by impressing the groove must go to the inside of the tile, because if it goes out the tile will not lay. Pressing it all inside without my new provision for supporting the inside surface results in spalling and cracking of the green tile, with a poor finished product, after burning.

20. The object of the present invention is a machine for impressing the desirable mortar groove in the end walls of a hollow ceramic tile without distorting the outside dimensions out of the straight lines given to them by the tile machine, in point of fact improving and correcting any 25. inequalities due to swelling as when the clay is a trifle damp.

25. I have more or less diagrammatically illustrated two forms of the invention which will satisfactorily carry out the objects stated, but 30. quite obviously either form can be varied widely without departing from the principles of the invention which are to be ascertained by the scope of the claims which I have made at the conclusion of this specification.

35. Drawings of both forms, as above noted, accompany and form a part of this disclosure, in which Figs. I to VIII inclusive are of what I have termed the cam type and Figs. IX to XIII inclusive illustrate the wheel type, the latter figures being further set out from the first type by using reference numerals from 100. While the wheel type is included in the generic claims, it is not specifically claimed in this application.

40. Fig. I is a side elevation of the feed or intake end of my new cam type indenting machine that will be useful in showing its principle and mode of operation;

45. Fig. II is the outgoing or discharge end of the structure shown in Fig. I, the right hand detail in this figure being the same one shown at the left of Fig. I;

50. Fig. III is a top or plan view of a portion of Fig. I to an increased scale;

Fig. IV is a plan view of a portion of Fig. II;

55. Fig. V is a section on line V—V of Fig. III;

Fig. VI is a section on line VI—VI of Fig. IV;

Fig. VII is a section on line VII—VII of Fig. V;

Fig. VIII is a section showing the end of an indented green tile with the indenting die just as the operation has been completed. 5.

Figures illustrating the wheel type are as follows:

Fig. IX is a plan view of the suitable machine for accomplishing the purposes of this invention, made proportionately a bit shorter than 10. will be expedient, to accommodate the view to the sheet;

Fig. X is an elevation in section on the line X—X of Fig. IX, with some parts omitted;

Fig. XI is a section taken on the line XI—XI 15. of Fig. X;

Fig. XII is an enlarged end view of one of the tile holding boxes hereinafter described in detail; and

Fig. XIII is a section on the line XIII—XIII 20. of Fig. XII with a part broken out to accommodate the view to the space.

Proceeding to describe the machine of the first or cam type, in detail; in the drawings it is deemed expedient to follow the progress of a 25. single tile through the machine since all will follow the same course.

In Fig. I, at the right hand top end, a tile box 1 is shown open at A with a green tile T₁ that has just been manually placed in position, 30. its nearest end being flush with the end of the tile box. At the next position, T₂, the lid 2 of the box has been closed and latched by the latch 3, see Fig. VII. T with a subscript is used to indicate the same tile in succeeding positions. 35

As noted, the tile T is placed with the near end flush with its corresponding end of the tile box 1, but to get just the right length, the tile from the moulding machine where it is made, not shown herein, is originally a little long and 40. as the tile box 1 progresses the long end is cut off by the piano wire W as shown also in Fig. III, no other detail being deemed necessary as cutting clay with a wire is standard practice.

The tile shown at T₃ is about to be trimmed 45. by the wire W and to prevent adhesion of the indenting die must next be given a light coat of oil on both ends, this being accomplished by the felt covered rollers R₁ and R₂, which will be supplied with oil by known means, as 50. needed.

To carry the tile box 1 from position to position, it is mounted on a belt B, preferably of four or five ply rubber conveyor type, which will be suitably mounted, such as the diagrammatic 55.

mounting shown, in which the standards 5 and 5a are provided with shafts 6 and 6a, upon which are journaled the pulleys 7 and 7a carrying the belt B to which the tile box 1 is attached at spaced intervals.

In the interests of accurate registration of tile and indenting die, the upper reach of the belt will run over the table 9, which keeps it in the proper horizontal plane.

10 The tile will now be presumed to have reached the position T6, see Figs. I and II; one end has been trimmed by the wire and both ends have been oiled to prevent sticking when indented or end grooved. It passes the indenting dies, to be later described, and the tile box 1 is opened when it reaches T9, is upended at T10 and is slid onto the conveyor 25 which runs alongside the belt B at the same speed.

15 We will now consider the indenting operation. 20 A sliding plate 30, see Figs. III, V and VII, is located inside the tile box 1 and is arranged to reciprocate, first to get out of the way of the wire W, the roller R1, and the roller R2, and finally to project equally on both sides of the 25 tile box 1. It is operable by the cam plate 32, working the roller 33. The cam plate begins just to the rear of position T3, Fig. I, ending at position T6.

20 The roller 33 is revoluble on the pin 34, journaled in the boxes 35 and 36, which latter are made rigid with the plate 30 by connections such as rivets 37 and 38, see Fig. V where slots are provided for the plate reciprocation.

25 It is easy to follow the movement of the plate from the layout in Fig. III.

30 The lower end of the pin 34 is provided with another roller 39 that cooperates with the flat leaf spring 40, which yields to the roller 39 as the plate is sent into different positions as shown in Fig. III, tending always to return the sliding plate 30 to mid-position, where it is left as the end of the cam plate 32 is reached, see the left hand end of Fig. III, by virtue of a central curved pocket 40a in spring 40.

35 This mechanism has been described in the singular number but each tile box 1 will be equipped with the same mechanism, hence they are plural in number but each works independently. It will be observed that the cam plate 32 begins and ends with the cam in central position 40 ready to timely engage the roller 33.

45 The purpose of the sliding plate 30 is to time the tile indenting mechanism, so that the impress of the indenting die will be equal and opposite at each end of the tile. Both ends must be indented by compression at the same time.

50 The die 50, see Fig. VIII, is a metal block formed with a positive bead 50a, and as an essential structure the supporting plug 50b which is I 60 believe entirely new and without which a tile cannot be successfully end grooved; the plug 50b is smaller than the inside of the tile to provide room for clay displacement occasioned by indenting the end groove; the plug being enough 65 smaller than the inside of the tile to accommodate the clay displaced in impressing the groove. The bead is positive to the negative groove 51. This tile is shown as a rectangular hollow tile but tile with central walls and more than one longitudinal hole are not excluded, merely requiring appropriate modification of the various mechanisms.

70 At the right hand end of Fig. IV, the plate 30 is shown extending equally on both sides of the tile box 1 and just after contacting the dies 50,

simultaneously at both ends of the tile box 1, which is closed and has a trimmed and oiled green tile in it.

75 The top and bottom of the die 50 are supplied with cam rollers 53, which have moved to the left, from initial position shown by the dotted circle indicated by the same numeral 53.

The die carriage 54 is mounted on slides 55, and springs 56 are compressed as it is moved to the left by the plate 30 when it will be forced into 10 operating engagement with the green tile completely as the die 50 reaches the position shown in dotted outline, at the left of its full line position, by contact of the roller 53 against the pivoted angle cam plate 57.

15 Shortly after leaving the position shown dotted, the roller 53 falls off the end of the angle cam 57, being abruptly withdrawn from the tile by influence of the spring 58. The spring 56 then asserts its superiority over spring 58 and returns 20 the die to its original position, by-passing the roller 53 underneath the angle cam 57, which yields to let it under, where it is in position for the next succeeding tile box that contacts it by its own plate 30.

25 The description has been of one end with its grooving die, only, but it will be understood that while the described operation has been taking place at one end of the tile box, an exactly equal but oppositely working set of mechanisms has 30 been grooving the other end of the green tile.

30 The following is a detailed description of the wheel type machine.

35 In the drawings, suitable mountings such as 101, 102, 103 and 104, here shown to be in the form of pedestals, are provided with shaft bearings 101a, 102a, 103a and 104a, in which are mounted the shafts 105 and 106.

40 The shaft 106 is broken away and will be presumed to be supplied with rotative power at proper speed and direction from a source not shown.

45 Mounted on the shafts 105 and 106 are pulleys 105a and 106a; and mounted on the pulleys is a heavy belt 107, preferably of five or six ply canvas and rubber construction.

50 Attached to the belt at spaced intervals are tile boxes 110 which are provided with an arcuate bottom portion 110a, to which the belt 107 is attached, here shown to be by rivets such as 107a in Fig. XII.

55 The arc of the bottom portion, 110a, is provided for suitable conformation with the surface of the pulleys 105a and 106a.

The tile box 110 is made to open on the hinge 55 111 by unlatching the latch 112a for the purpose of putting a green tile in, which is then latched in place as hereinafter explained, and for taking it out after the ends are impressed with the mortar groove, also explained more fully 60 hereinafter.

65 The tile box is also hinged at one end to the bottom plate 110b by the pivot pins 112 and 113, in such manner that it may be up-ended to discharge its contents as shown at the lefthand top part of Fig. X. The contents will be discharged onto a belt 114, alongside the belt 107, running on the pulley 105a, at one end and on another pulley, not shown, some distance ahead of the lefthand end of the machine. The belt 70 114 serves to convey the indented green tile toward a point where they are dried preliminary to firing.

75 Rigidly mounted on a suitable foundation, on each side of the belt 107, are two pedestals, 115

and 116, see Fig. XI, and rotatably mounted on the pedestals are oppositely mounted spiders 117 and 118, which are pivoted to the pedestals 115 and 116 by the pivots 115a and 116a.

5 The spiders 117 and 118 are duplicates, except as with respect to the actuating arms A thereon; they are right and left. Each spider is provided with a plurality of radial arms, Ra, and die members for indenting the tile ends, indicated by the numeral 125, common to all of the dies since they are alike.

10 The dies 125, are provided with a generally arcuate surface, which is composed of a metal support 125a, employing somewhat of the principle of a gear tooth, because it must roll into the hollow of a tile and support the inside of it while the groove is being swaged into the end of the green tile so that the tile will not crumble or spall. The necessities of the indenting process are very clearly shown in Fig. XI at the top center where 125a is supporting the inside surfaces of the green tile while the indenting die portion, 125b, as shown, is a bead that is a counterpart of the groove required.

15 20 25 Each tile box 110 is equipped with an extension plate 110c and the hinged portion of the box is equipped with a latch 110d that cooperates with the extension plate 110c to hold the box open during a part of the operation, which will be described.

30 Considering Fig. X. One tile box 110 is shown in position directly over the vertical axis of the pulley 105a, which is the loading position. A green tile will be manually placed in the open box, so that the lefthand end is flush with the lefthand end of the box. The green tile are a trifle over length for subsequent trimming to exact length by the tension wire T, shown in position for the purpose in Figs. IX and X, just to the left of the second box.

40 After placing the green tile in the box as described, the box is closed and latched as shown in the next succeeding position to the left; in the third position the tile has been trimmed and in the fourth position the tile is receiving the mortar grooves at both ends, as more clearly shown in Fig. XI.

45 After leaving the grooving position, the box is unlatched as shown, then the part that is pivotally hinged on the pivot pins 112 and 113 is opened as shown in the next two positions, the indented tile is deposited on the belt 114 and the pivotally hinged box portion, being restored to its normal position, traverses the reversely running reach of the belt 107, for repetition indefinitely.

50 The spiders are equipped with the curved arms A, that are contacted by the lugs Aa. The designs of the lugs, the curved actuating arms and cooperating spacing so that accurate timing can be had, is a very important matter. It has been carefully worked out and the proportions on the drawings, Fig. IX are reliable.

55 The arms A are of such length and position that when one arm A is about to be released by its lug Aa due to travel of the belt 7 to which the lugs Aa are securely attached in spaced relationship, then another arm A will be in position to be engaged by the next succeeding lug Aa, after the manner of successive engagement and release of gear teeth.

60 A plate 130 will be suitably supported under the center portion of the upper reach of the belt, to support the boxes 110 in proper alignment 65 with the grooving dies as shown and described.

The reason the spiders are run with contact of the tile boxes instead of timing gears, in step with the belt driving means, is because invariably there will be some belt slippage which would ruin the timing. Spacing the boxes on the rubber belt accurately enough for proper timing is believed impossible, due to belt stretch, even temperature changes being sufficient to disrupt the orderly operation unless, as I have shown, each tile box times its own die.

10 15 With the structure I have shown and described, it is sufficient that the boxes be far enough apart. A metal link belt wears and gets longer and unless made of very expensive materials will be quite subject to rust in a clay mill.

20 The speed of the pulleys 105a and 106a should be under the control of a clutch or a speed changer, until the operatives acquire the requisite skill in handling the tile into and out of the machine.

25 Having disclosed my invention so that anyone familiar with the art to which it appertains may make and use it, what I claim as new and desire to secure by Letters Patent, is:

1. A machine for end grooving hollow rectangular tile, comprising a movable carrier, rectangular tile boxes open at both ends spaced on said carrier, grooving dies movably mounted in cooperative relationship with said carrier and said boxes and timed operating means for the dies effective to bring them into and out of contact with tile carried in the boxes while the said boxes are in motion.

30 35 40 45 2. A machine for end grooving hollow rectangular tile, comprising a movable carrier, rectangular tile boxes closed on the sides and open at the ends spaced on said carrier and end grooving apparatus adjacent said carrier, said grooving apparatus being so positioned with respect to the carrier and boxes that the open ends of said boxes will be brought in alignment with said apparatus upon movement of the carrier whereby seriatim to impress grooves in the exposed ends of the tile in said boxes.

50 55 60 65 3. A machine for end grooving hollow rectangular tile comprising a movable carrier, close fitting tile boxes open at both ends spaced on said carrier grooving dies and timed operating means effective to move the grooving dies into forcible contact with tile carried by the boxes through both ends thereof, the said dies having formed thereon a positive grooving bead and a plug support for the inside of the tile of similar section but smaller than the inside of the tile.

70 75 80 85 4. In a machine for upsetting mortar grooves in the end walls of green hollow tile, a box member that is adapted to contain a green tile in close conformity with its outside surfaces but leaving its ends uncovered, a belt member on which said box is mounted for horizontal movement, a sizing means for cutting a contained tile to length, embossed bead die members that include inside wall supporting means that are adapted to contact both ends of a tile simultaneously when it is contained in the box and interengaging parts on the die and the box to time the movement of the die with the box.

5. An end indenting machine for hollow tile, comprising a carrier member, means for transmitting linear movement to the carrier, a plurality of tile boxes spaced on the carrier that fit the external outline of a tile, oppositely mounted cam operated die members to impress groove making dies into the end wall surfaces of

the tiles simultaneously as the tile boxes pass a selected point and transmissions to bring the dies into and out of contact with a tile under influence of power supplied from the carrier.

- 5 6. In a tile grooving machine, a belt mounted for generally horizontal movement of its upper reach, a plurality of tile boxes spaced on said belt, a grooving die of the character described that is mounted for horizontal and reciprocating movement to indent tile carried in the boxes and cooperative transmissions in part carried by each tile box that are effective to energize the end grooving means in timed relationship to the travel of the tile box.
- 10 7. In an end mortar grooving machine for hollow tile, a belt member, means for moving the belt member, tile boxes in spaced position on the belt member that are adapted to contain green hollow tile, end grooving dies mounted to successively contact the ends of tile carried in the tile boxes at both ends simultaneously to impress a mortar groove into the end walls of carried green tile, means for interengaging and timing the dies with each tile box seriatim and cam means for moving the dies into and out of contact with carried green tile.
- 15 8. The combination according to claim 7 and including a cutting wire positioned to cut carried green tile to a predetermined length before they are contacted by end grooving means.
- 20 9. A grooving die for a tile machine comprising a die member provided with an embossed groove making bead in combination with a sup-

port for the inside of a green tile being grooved, comprising a rectangular block member that is smaller than the rectangular opening in a green tile, to support the inside of the tile, open end tile box means for supporting the outside of the tile while being grooved and means for bringing the die and block into and out of contact with a green tile to impress a groove in its end walls.

5 10. In a tile indenting machine of the character described, a movable belt member, means for moving the belt in a straight line, a plurality of tile boxes attached to said belt at spaced intervals, indenting dies mounted to move into and out of engagement with carried tile to indent the tile as they pass a selected zone and a timing 10 arrangement for bringing the dies timely into engagement with the contents of a tile box that is operated by contact of a part carried by the belt with a part made rigid with the die mounting.

15 11. In a machine for upsetting a mortar groove in the end walls of a hollow green tile, an end grooving die that is provided with embossed groove beads that are positive to the grooves required and that includes an inside wall support member smaller than the inside of the tile positioned to extend into a tile beyond the influence of the beads, to support and shape material displaced by the grooving beads in combination with outside wall support tile boxes that 20 prevent displaced material from going outwardly.

25 JAMES D. THOMPSON.
